STOKER

John Gehl, Denmark, Wis.

Application February 9, 1940; Serial No. 318,060

1. Claim. (Cl. 110—45)

This invention pertains generally to stokers of the automatic underfeed firing type, and more particularly to retorts employed in such stokers.

The invention has primarily for its object to improve stoker retorts with respect to increased efficiency of combustion and consequent economy of fuel.

Incidental to the foregoing, a more specific object of the invention resides in the provision of a retort equipped with a centrally mounted combustion tube, for greater distribution of air through and over the fuel bed to insure maximum combustion, and a more uniform distribution of fuel within the retort and combustion chamber.

Another object resides in the provision of means carried by the combustion tube for directing and regulating air supplied for secondary combustion above the fuel bed, thus substantially consuming all fuel gases to provide maximum efficiency.

With the above and other objects in view, which will appear as the description proceeds, the invention resides in the novel construction, combination, and arrangement of parts, substantially as hereinafter described, and more particularly defined by the appended claim, it being understood that such changes in the precise embodiment of the herein disclosed invention may be made as come within the scope of the claim.

In the accompanying drawing is illustrated one complete example of the physical embodiment of the present invention constructed according to the best mode so far devised for the practical application of the principles thereof.

In the drawing:

Figure 1 is a vertical section through a retort constructed in accordance with the present invention, the view being taken on the line 1—1 of Figure 2;

Figure 2 is a horizontal section taken on the line 2—2 of Figure 1;

Figure 3 is a detail section taken on the line 3—3 of Figure 1; and

Figure 4 is a detail section taken on the line 4—4 of Figure 1.

Referring now more particularly to the accompanying drawing, the numeral 1 designates generally a retort, set within a refractory casing 2 forming a combustion chamber.

The retort 1 comprises an annular shell 3, terminating at its upper end in a flange 4, which carries an inner bowl 5, the bottom of which is spaced from the bottom of the shell 3.

The retort is provided in its side wall with a feed opening 6 communicating with a feed tube 8, in which a conventional screw conveyor 9 is positioned to deliver green fuel to the bowl 5.

Connected with the retort between the bottom of the bowl 5 and the shell 3 is a forced draft pipe 10, preferably flattened horizontally, to supply air to a compartment 11 formed between the shell 3 and the bowl 5.

The bowl 5 is provided with spaced air admission ports 12, which allow air delivered to the compartment 11 to enter the bowl and pass through the fuel bed supported by the bowl.

Mounted centrally within the bowl 5 is a combustion tube 13, flared at its upper end, and provided throughout its height with spaced discharge ports 14. As will be noted in Figure 1, the lower end of the combustion tube is open to receive air delivered to the compartment 11, which, as stated, is discharged into the fuel bed through the ports 14.

It will be noted that the combustion tube in cross section has a circular rear wall intersected by front converging walls which form a 25 knife-edge splitting blade for the fuel as it is fed to the bowl through the mouth of the fuel feed pipe, which pipe points toward it. Thus the flow of fuel, with a minimum of resistance, is loosened up and divided to develop a porous 30 body through which air is readily admitted from the bowl sides.

The upper edge of the combustion tube is provided with annularly spaced, arcuate notches 15 formed tangentially to the axis of the tube. 35 Threaded into a spider 16, formed in the upper part of the combustion tube, is a cap plate 17, which may be vertically adjusted to regulate the opening between the top of the tube and the plate, to control the volume of air discharged from the upper end of the tube.

As will be noted in Figures 1 and 4, the bottom face of the plate 17 is provided with a plurality of radial arcuate grooves 18, which cause air deflected horizontally by the plate to swirl over the top of the fuel bed B. Swirling action of air discharged at the top of the combustion tube is further augmented by the tangential arcuate notches 15 in the upper edge of the combustion tube.

50 Preferably, that side of the cylindrical tube 13 facing the feed opening 7 is tapered to an edge 13'. Thus, as fuel is fed into the bowl 5 and contacts the tube 13, not only is resistance to the feed reduced, but the fuel is divided and directed to opposite sides of the retort, thus bringing about

a uniform distribution of fuel in both the retort and combustion chamber, and, consequently, more even combustion.

In operation, green fuel is fed to the bowl 5 of the retort 1 through the feed tube 8 by the screw conveyor 9, and, as the same is forced upwardly, it gradually becomes coke above the retort; during which operation, gases are liberated which pass up through the fuel bed, and are consumed at the top of the bed by secondary combustion.

Obviously, air distributed into the fuel bed through the ports 12 in the bowl 5, and the ports 14 in the central combustion tube 13, will uniformly pass through the fuel bed to bring about the most efficient initial combustion, resulting in gradual coking of the fuel; and, as the fuel gases are released during the coking operation, they must pass upwardly through the top of the bed, which is substantially incandescent. While the greater portion of liberated gas is consumed by the incandescent crust at the top of the fuel bed, such gas as may escape contacts the forced swirl of air discharged horizontally between the upper edge of the combustion tube and the cap plate 7 to bring about secondary combustion, with the result that practically all fuel gases are consumed, thus providing maximum efficiency and fuel economy.

From the foregoing explanation considered in connection with the accompanying drawing, it will be seen that a highly improved stoker retort

has been provided at small additional cost over conventional retorts, which not only provides economy of operation, but also reduces smoke nuisance.

5 I claim:

In a furnace having a circular combustion chamber, a stoker retort comprising a circular shell nested within the chamber and having a bottom wall, a flange extending inwardly from the top edge of the shell, a circular bowl depending from the flange and having a bottom wall terminating short of the bottom wall of the shell, said bowl having a plurality of air admission ports communicating with the air space between the shell and bowl, a fuel feed tube extending radially through the shell wall and communicating with the bottom portion of the bowl, a forced draft pipe communicating with the air space between the bottom of the shell and said bowl bottom, a vertical combustion tube centrally mounted in the bowl bottom and communicating with the said air space and having air discharge ports therethrough, the last named tube in cross section opposite the said fuel feed tube being formed with a circular rear wall and tangential side walls extending forwardly therefrom and converging to a splitting point opposite the mouth of the fuel feed tube, whereby the fuel fed into the bowl is broken up as it flows past the pointed edge of the combustion tube to break and loosen the mass and form air passages throughout the same.

JOHN GEHL.
